UNITED STATES PATENT OFFICE

2,145,268

APPARATUS FOR FOOD PROCESSING

John Mills, Philadelphia, Pa., assignor, by mesne assignments, to Crown Can Company, Philadelphia, Pa., a corporation of Pennsylvania

Application September 14, 1936, Serial No. 100,760

12 Claims. (Cl. J9—251)

The principal object of the invention is to provide a machine for sterilizing canned food products.

Another object of the invention is to provide a machine for sterilizing canned food products having a header for receiving the open can ends equipped with a valve of improved construction for controlling the vacuumizing and sterilizing of the container.

10 A further object of the invention is to provide a machine of the above character which is of simple construction, and which is unlikely to become fouled with the food products during the vacuumizing and sterilizing operations.

15 Ancillary to the above object, it is a further object of the invention to provide a machine of the above character in which the container receiving valve and vacuum creating means may be removed for cleaning with facility.

20 More specifically, the present invention relates to improvements in the construction of machines of the type disclosed in my Patent Nos. 2,054,092 and 2,054,093 issued September 15, 1936. In my Patent No. 2,054,092, a sterilizing and can sealing

25 machine of the continuous operating type is disclosed which comprises generally a rotatively driven drum or turret constructed to progressively receive a plurality of containers which, prior to delivery thereto have been filled with an edible. During the operation of the machine, these containers are brought into engagement with the valve header where fluid communication with the interior of the container is effected. In the early portion of the operating cycle of the

30 turret a partial vacuum is created in the valve header which causes rarification of the gases within the container. In the latter portion of the operating cycle of the turret, steam under pressure is injected into the containers which causes the contents thereof to be violently agitated and heated to a relatively high temperature.

In my above-mentioned patent, the mechanism provided to exhaust the air from the containers was connected to a manifold, common to the steam exhaust line, and formed with the conduits which led to each of the valve headers.

45 Steam lines were also connected with each of the headers and exhaust lines led therefrom to an exhaust manifold. The structure further embodied control cams, and operating linkage which was organized to successively actuate steam and vacuum valves within the headers and govern the period during which each of the valves was retained in its open position.

50 In my Patent No. 2,054,093, which is an im-

5 provement over my Patent No. 2,054,092, a can sealing machine is disclosed in which a partial vacuum is automatically created within each of the headers upon the adjustment of an exhaust steam valve associated therewith. The machine of this patent eliminated the vacuum valves employed in Patent No. 2,054,092, and also the unit for creating a vacuum, the conduits therefor and the operating linkage, thus providing material economy in the production and erection of the 10 machine.

The present invention is a further improvement on the machine disclosed in Patent No. 2,054,093, the improved form of header with its vacuum valve further simplifying the construction of 15 the apparatus and eliminating the steam and vacuum lines employed in that patent. The construction of the present invention is of outstanding advantage in its simplicity, in that there is little likelihood of the working parts of the header 20 becoming fouled, and said parts are so arranged that they are readily available for cleaning, without dismantling the machine.

In the drawings, which are illustrative of a preferred form of the invention and in no sense 25 restrictive:

Figure 1 is a partial vertical sectional view of the machine;

Fig. 2 is an enlarged vertical sectional view of a portion of the machine shown in Fig. 1, disclosing 30 the header construction;

Fig. 3 is an end elevation view of Fig. 2, showing the rotatable drum which carries the valve headers;

Fig. 4 is a view taken along the line 4—4 of Fig. 35 2, showing the face of the fixed plate carried by the machine frame; and

Fig. 5 is an enlarged view showing a container of the type operated upon by the machine of the present invention, and its association with the 40 valve header.

Referring to Fig. 1, the machine is shown as comprising a frame 10 having at the upper end thereof a bushing 12 within which is keyed a hollow shaft 14. Mounted for rotation on the 45 hollow shaft is a turret 16. The turret is rotated at appropriate speed about the shaft 14 from the power shaft 16 which is journaled in the lower portion of the frame. Shaft 16 is driven in any suitable manner as by the pulleys 50 18, and is equipped with a drive pinion 20 which meshes with an idler gear 22, which in turn engages the gear teeth 24 disposed about the periphery of the turret 16.

The turret is provided on the front face and 55

adjacent the periphery thereof with a plurality of brackets 26, said brackets having mounted thereon a plurality of container supporting platforms 28. Each of the container supporting platforms has attached to the lower side thereof a plurality of rods 30 which pass through apertures 31 in the brackets 26, said rods being attached to a block 32 disposed outside of the brackets. Each of the blocks 32 carries a roller 34 which is adapted to engage beneath a cam track 36 carried by the frame during a portion of the cycle of the turret for a purpose which will hereinafter appear. The inner end of the bracket 26 is provided with a bore 40, in which bore is positioned a spring 42, the inner end of

15

any suitable clinching devices for permanently sealing the containers. These devices may comprise movable jaws which engage the elevated part 50 of the container top and crimp and force the same under the movable valve member 54 in 5 the manner disclosed in my above-mentioned patent.

Referring to Figs. 1 and 2, the valve headers 56 are shown integrally formed with a housing 58 comprising a rotatable drum, said drum being 10 mounted for rotation upon a shaft 60 which is fixed within the shaft 14, and being driven from turret 16 by means of pins 61 extending from the outer wall of the turret and entering openings 63 in the inner wall of the drum, as shown in Fig. 2. 15

through an annular plate 94 secured for rotation with the inner face of the rotary drum.

Disposed within each passage 90 is an ejector comprising a Venturi tube 96, the outer end of said tube being in alignment with and spaced from the inner end of a removable jet member 100, each of said jet members communicating at their outer ends with the annular chamber 64 of the main gas chamber. A passage 102 connects each of the auxiliary gas chambers 76 at their inner ends with the respective passages 90, passages 102 joining passages 90 at points between the jet members 100 and the Venturi tubes 96.

The outer end of the hollow shaft 14 is flared outwardly as shown at 164, and on the outer face of the flared out portion is fixed a circular plate 106 of the type shown in Fig. 4. The plate 106 has an opening 108 therethrough, said opening extending through an arc of substantially 80°. However, this arc may be of shorter or more extended dimension depending upon the duration of vacuumizing desired, as will later appear. Plate 106 with its opening 108 forms a plurality of slide valves with plate 94 and its openings 92.

When the containers are disposed in abutting relation with respect to the valve header as shown in detail in Fig. 5, the extending portion 50 of the container top will seal with an annular sealing ring 110 disposed around the fluid-way 82, and the engagement of the container valve member 54 with the valve member 84 of the header will force the container valve member from its seat, and will also move the valve 78 inwardly against the tension of the spring 88 to open the fluid-way 82.

With the containers so disposed, rotation of the turret will cause the opening 92 of a particular valve header to pass the arcuate opening 108 in the fixed plate 106, and gas from the main chamber of the rotary drum will pass through the jet 100 into and through the Venturi tube 96, through the openings 92 and 108 into the exhaust passage 112 within the hollow shaft 14, which passage may connect with a suitable condenser. This flow will cause a partial vacuum in the passage 102, creating a suction in the auxiliary chamber 76, which in turn will draw gases from the interior of the container through the fluid-way 82, it being understood that during this portion of the cycle the container valve and header valve will be in open condition.

It will be noted that the arcuate opening 108 is in the lower portion of the fixed plate 106, so that the vacuumization of the containers will take place when the latter are in right side up position.

After the particular passage 92 in the rotary plate 106 has traversed the arcuate opening 108 in the fixed plate 106, the flow of gas through the Venturi tube 96 will cease, and the gas from the main reservoir will then flow through the jet 100, passage 102, auxiliary chamber 76, and through the fluid-way 82 into the container.

It will be apparent from Fig. 4 that at this stage of the cycle, the containers will be approaching a position in which the contents will have arisen to a point adjacent the container opening 52, but the inrush of steam will prevent any flow of the container contents into the auxiliary chamber 76.

The flow of steam into the container will continue during the subsequent rotation of the drum, and as the container is being gradually turned to bottom-side-up position, the steam or gas will pass into and through substantially all parts of

the liquid in the container and causing a violent agitation of said liquid, resulting in a rapid increase in temperature of the contents and thorough sterilization. When a particular container is rotated through the sterilizing cycle and is brought to position on the lower part of the cycle where it is to be discharged as shown in Patent No. 2,054,092, the roller 34 will engage beneath the cam track 36 withdrawing the container from abutting engagement with its respective valve header, at which time the pressure of the steam within the container will cause the closing of the container valve member 54. The pressure of steam within the chamber 76 and the action of spring 42 will move the valve 78 to close the fluid way 82 when the container is removed, thus preventing escape of steam.

Referring to Fig. 2, it will be observed that the circular plate 94 carried by the rotary drum will be held in intimate engagement with the outer face of the fixed plate 106 by a spring 114 which engages at its inner end around a hub 106 of the rotary drum, said spring being retained at its outer end by a follower 116 mounted upon the pin 118 secured to the outer end of the fixed shaft 60. Follower 116 abuts against a thrust bearing 120 which is carried by the pin 118. Suitable packing 122 may be provided around the shaft 60 where it provides a journal for the rotary drum, thus preventing leakage of gas along the shaft.

It will be apparent that by reason of the removability of the cap 80 on the valve header, the valve 78 may be removed for cleaning the same and also for cleaning of the interior of the auxiliary gas chamber 76. Furthermore, referring particularly to Figs. 2 and 3, it will be observed that removable end plates 126 are provided in alignment with each of the jet members 100, so that upon removal of the end plates 126 the jet members and Venturi tubes 96 may be removed for cleaning.

While the operation of the machine will be apparent from the above description, a brief summary of the same is as follows:

The containers of the type disclosed in Fig. 5 will be fed to the platforms 28 while a particular platform is near the lower end of the cycle, and prior to the time that the opening 92 of the particular valve header is in registry with the arcuate opening 108 in the fixed plate 106. When a container is fed to a platform 28, the same will be in retracted position by reason of the engagement of the roller 34 with the cam track 36. Subsequent rotation of the drum will remove roller 34 from track 36 at which time the spring 42 will elevate the container into abutting engagement with the face of the valve header. At this time, both the container valve and header valve will be in open condition as illustrated in Fig. 5, and further rotation of the turret will bring the passage 92 into registry with the opening 108, and during the traversing of opening 108 by passage 92, the flow of gas through the Venturi tube will cause a partial vacuumizing of the container by the withdrawal of gases therefrom. Further rotation of the turret will result in the closing of the passage 92, after which time the steam will pass into the container to sterilize the contents. The sterilization will continue until the particular container is on the downward side of the cycle, at which time the engagement of roller 34 with cam track 36 will retract the container and permit the closing of the container valve under pressure of steam or other gas within the container. The containers will then be removed from the 75

platform 28, and subjected to the permanent closing operation in the manner previously referred to.

It will be apparent that various modification 5 of the construction and manner of operation herein disclosed may be made without departing from the invention.

I claim:—

1. In an apparatus of the character described, 10 a frame including a fixed plate having an opening therein, a rotary turret including a drum mounted for rotation on said frame, said drum comprising an annular main chamber filled with gas at all times and a rotary plate which engages 15 said fixed plate, a plurality of valve headers on said drum, each header including an auxiliary gas chamber constantly in communication with the main gas chamber through a gas inlet in said header, and a container engaging valve, a plurality 20 of container supporting platforms on said turret, means for moving said platforms during rotation of said turret to engage the open ends of the containers with said valves to open the same, means included in said drum for creating suction in said containers through said valves and operating means for said suction creating means including an opening in said rotary plate at each of said headers, said openings registering with the opening in said fixed plate to successively 25 vent the gas from each of said auxiliary gas chambers during a portion of the rotation of said turret, to create suction in said containers through said valve headers being such that 30 gas is forced under pressure from said chambers into the containers during subsequent rotation of said turret and when said openings are out of register.

2. In an apparatus of the character described, 35 a frame including a fixed plate having an opening therein, a rotary turret including a drum mounted on said frame, a valve header on said drum, a gas inlet to said header, a wall of said header including a plate engaging said fixed plate and having an opening adapted to register with the opening in said fixed plate during a portion 40 of the rotation of said turret, mechanism on said turret for supporting a container in abutting engagement with said header, a valve in said header for effecting communication between the header and the container, and means within said header for creating a partial vacuum therein when said openings are in register.

3. In an apparatus of the character described, 50 a frame including a fixed plate having an opening therein, a rotary turret including a drum mounted on said frame, a valve header on said drum, a gas inlet to said header, a wall of said header including a plate engaging said fixed plate and having an opening adapted to register with the opening in said fixed plate during a portion 55 of the rotation of said turret, mechanism on said turret for supporting a container in abutting engagement with said header, a valve in said header for effecting communication between the header and the container, and means within said header comprising a Venturi tube and a steam jet for creating a partial vacuum therein when said openings are in register.

4. In an apparatus of the character described, 65 a frame including a fixed plate having an opening therein, a rotary turret including a drum mounted for rotation on said frame, said drum comprising an annular main chamber filled with gas at all times and a rotary plate which engages 70 said fixed plate, a plurality of valve headers on said drum, each header including an auxiliary gas chamber constantly in communication with the main gas chamber through a gas inlet 75 in said header, and a container engaging valve,

a plurality of container supporting platforms on said turret, means for moving said platforms during rotation of said turret to engage the open ends of the containers with said valves to open the same, means included in said drum for creating suction in said containers through said valves and operating means for said suction creating means including an opening in said rotary plate at each of said headers, said openings registering with the opening in said fixed plate to successively 10 vent the gas from each of said auxiliary gas chambers during a portion of the rotation of said turret, to create suction in said containers through said valve headers being such that 15 gas is forced under pressure from said chambers into the containers during subsequent rotation of said turret and when said openings are out of register.

5. In an apparatus of the character described, 20 a frame including a fixed plate having an opening therein, a rotary turret including a drum mounted on said frame, a valve header on said drum, a gas inlet to said header, a wall of said header including a plate engaging said fixed plate and having an opening adapted to register with the opening in said fixed plate during a portion of the rotation of said turret, mechanism on said turret for supporting a container in abutting engagement with said header, a valve in said header for effecting communication between the header and the container, and means within said header for creating a partial vacuum therein when said openings are in register, the construction and arrangement of said valve header being such that 35 gas is forced under pressure from said header into the container when said openings are out of register.

6. In an apparatus of the character described, 40 a frame including a fixed plate having an opening therein, a rotary turret including a drum mounted on said frame, a valve header on said drum, a gas inlet to said header, a wall of said header including a plate engaging said fixed plate and having an opening adapted to register 45 with the opening in said fixed plate during a portion of the rotation of said turret, mechanism on said turret for supporting a container in abutting engagement with said header, a valve in said header for effecting communication between 50 the header and the container, and means within said header comprising a Venturi tube and a steam jet for creating a partial vacuum therein when said openings are in register, the steam from said jet passing into the container through 55 said header valve to sterilize the contents thereof when said openings are out of register.

7. In an apparatus of the character described, 60 a frame including a horizontal shaft and a fixed plate having an opening therein, a turret mounted for rotation on said shaft, said turret including a drum comprising an annular main chamber filled with gas at all times and a rotary plate which engages 65 said fixed plate, a plurality of valve headers on said drum, each header including an auxiliary gas chamber constantly in communication with the main gas chamber through a gas inlet in said header, and a container engaging valve, a plurality of container supporting platforms on said turret, means for moving said 70 platforms during rotation of said turret to engage the open ends of the containers with said valves to open the same, means included in said drum for creating suction in said containers through said valves and operating means for 75

5 said suction creating means including an opening in said rotary plate at each of said headers, said openings registering with the opening in said fixed plate to successively vent the gas from each of said auxiliary gas chambers when said chambers are at the lower portion of the cycle of rotation of said turret, to create suction in said containers through said valve.

8. In an apparatus of the character described, 10 a frame including a horizontal shaft and a fixed plate having an opening therein, a turret mounted for rotation on said shaft including a drum, a valve header on said drum, a gas inlet to said header, a wall of said header including a plate engaging said fixed plate and having an opening adapted to register with the opening in said fixed plate when said header is at the lower portion of the cycle of rotation of said turret, mechanism on said turret for supporting a container in abutting engagement with said header, a valve in said header for effecting communication between the header and the container, and means within said header for creating a partial vacuum therein when said openings are in register.

9. In an apparatus of the character described, 15 a frame including a horizontal shaft and a fixed plate having an opening therein, a turret mounted for rotation on said shaft, said turret including a drum, a valve header on said drum, a gas inlet to said header, a wall of said header including a plate engaging said fixed plate and having an opening adapted to register with the opening in said fixed plate when said header is at the lower portion of the cycle of rotation of said turret, mechanism on said turret for supporting a container in abutting engagement with said header, a valve in said header for effecting communication between the header and the container, and means within said header comprising a Venturi tube and a steam jet for creating a partial vacuum therein when said openings are in register.

10. In an apparatus of the character described, 20 a frame having a rotary turret including a drum mounted thereon, said drum comprising an annular main chamber filled with gas, a plurality of valve headers on said drum, each header including an auxiliary gas chamber, said headers each having a container engaging valve, a plurality of container supporting platforms on said turret, means for moving said platforms during rotation of said turret to engage the open ends of the containers with said valves to open the same, and means for venting the gas from each of said auxiliary chambers at high velocity during a portion of the rotation of said turret, to create suc-

tion in said containers through said container engaging valve, including a slide valve which opens to vent the gas from said auxiliary gas chambers, said slide valve including a valve member on said frame and a cooperating valve member on said drum at each of said headers. 25

11. In an apparatus of the character described, 30 a frame having a rotary turret including a drum mounted thereon, said drum comprising an annular main chamber filled with gas, a plurality of valve headers on said drum, each header including an auxiliary gas chamber, said headers each having a container engaging valve, a plurality of container supporting platforms on said turret, means for moving said platforms during 35 rotation of said turret to engage the open ends of the containers with said valves to open the same, means for venting the gas from each of said auxiliary chambers at high velocity during a portion of the rotation of said turret, to create 40 suction in said containers through said container engaging valve, including a slide valve which opens to vent the gas from said auxiliary gas chambers, said slide valve including a valve member on said frame and a cooperating valve member on said drum at each of said headers, and means for urging said slide valve members into engagement with one another. 45

12. In an apparatus of the character described, 50 a frame having a rotary turret including a drum 50 mounted thereon, said drum comprising an annular main chamber filled with gas, a plurality of valve headers on said drum, each header including an auxiliary gas chamber, said headers each having a container engaging valve, a plurality of container supporting platforms on said turret, means for moving said platforms during 55 rotation of said turret to engage the open ends of the containers with said valves to open the same, and means for venting the gas from each of said auxiliary chambers at high velocity during a portion of the rotation of said turret, to create 60 suction in said containers through said container engaging valve, including a slide valve which opens to vent the gas from said auxiliary gas chambers, said slide valve including a valve 65 member on said frame and a cooperating valve member on said drum at each of said headers, said slide valve closing to terminate the venting of gas from each of said auxiliary gas chambers during a subsequent portion of the rotation of said turret, whereby gas is forced under pressure from said auxiliary gas chambers through their container engaging valves into the containers. 70

JOHN MILLS. 75
